UNITED STATES PATENT OFFICE.

SIDNEY J. ORNSTON, OF NEW YORK, N. Y.

DEVICE FOR SECURING WIRE BINDERS.

Application filed January 11, 1924. Serial No. 685,515.

To all whom it may concern:

Be it known that I, SIDNEY J. ORNSTON, a citizen of the United States, and a resident of the borough of Bronx, county of Bronx, 5 city and State of New York, have invented certain new and useful Improvements in Devices for Securing Wire Binders, of which the following is a specification sufficient to enable those skilled in the art to which the 10 invention appertains to utilize the same.

While adapted for use in connection with wire binders for various analogous purposes, my improved wire tightening and securing device is designed primarily for tightening 15 and securing wire binders around and upon wooden boxes in a more convenient, expeditious and effective manner than theretofore,—the invention consisting essentially in the specific combination, construction and 20 arrangement of parts and appurtenances described and claimed, whereby these and other advantageous results are attained, and a distinctive feature being the duplex character of the implement whereby both extremities of a binding wire are manipulated 25 simultaneously, all as hereinafter fully set forth.

In the accompanying drawings I exemplify a practical embodiment of the essential features of my invention, although I do not 30 limit myself to the identical form and construction of component parts shown, since modifications in minor details, and equivalent mechanical expedients may be resorted 35 to with like results and without departing from the spirit and intent of my invention in this respect.

With this understanding:—

Fig. 1, represents a top view of my improved device for securing binding wires;

Fig. 2, a front elevation thereof;

Fig. 3, an end elevation of the device;

Fig. 4, is a transverse sectional elevation taken upon plane of line 4—4 Fig. 1;

Fig. 5, is a transverse sectional elevation taken upon plane of line 5—5 Fig. 1;

Fig. 6, is a transverse sectional elevation taken upon plane of line 6—6 Fig. 1;

Fig. 7, is a diagrammatic plan illustrating the method of applying and gripping the extremities of a wire binder;

Fig. 8, is a similar view, illustrating the corrective convolutions imparted thereto;

Fig. 9, is a diagrammatic front view of the part shown in Fig. 7;

Fig. 10, is a perspective view in detail of the lock gear;

Fig. 11, is a detail view, on a larger scale, of the corrective twist convolutions imparted to the ends of the binding wire;

Fig. 12, is a horizontal section taken upon plane of line 12—12 Fig. 2;

Fig. 13, is a vertical sectional elevation taken upon plane of line 13—13 Fig. 4;

Fig. 14, is a detail illustrating the actuation of shearing off the superfluous ends of the wire binder;

Fig. 15, is a detail perspective of the twister gear.

The basic frame work consists of the longitudinal spine member B, having the rear extensions b', b², b³ and b⁴, and the frontal extensions b⁵, b⁶. On and between the said rear extensions b', b², b³, is mounted the wire tension power shaft P, on the left hand extremity of which is fulcrumed the hand lever H, carrying the spring pawl h, which engages with the ratchet-wheel p, rigidly mounted on the said hand power shaft P, p', being a detent pawl pivotally mounted 80 on the outer side of the base extension b', and engaging peripherally with the said ratchet wheel p', as shown more particularly in Fig. 3, of the drawings. Hence reciprocal movement of the hand lever H, 85 will rotate the shaft P, intermittently, affording power and actuation to the other operative parts of my binding implement, considering the latter in a unitary sense.

Transmission pinions p², p³, rigidly attached to the intermittently rotatable power shaft P, mesh with the mitre gears g³, g⁴, rigidly attached to the rear ends of the counter shafts g', g², which latter are journaled in the aforesaid frontal extensions b⁵, b⁶, of the base B. Rigidly secured to the said ends of these countershafts g', g², are the twin wire gripping discs G', G², formed with the radial face slots g*, g², for engagement with the extremities of the binding wire w, as shown more particularly in Fig. 9, of the drawings.—the ends of said bind-

ing wires w , being bent and inturned diagonally against the discs G' , G^2 , within the gripping slots g^x , g^y , on opposite sides of the faces of the said twin discs G' , G^2 , so that the rotation thereof tends to clinch the ends of the wire. In this connection it is to be noted that the transmitting pinions p^2 , p^3 , are opposed in position with relation to each other, and mesh with opposite sides of their respective mitre gears g^3 , g^4 , so that the countershafts g' , g^2 , and the grip discs G' , G^2 , will rotate simultaneously in opposite directions when the lever H , is manipulated.

15 B', B^2 , B^3 , B^4 , are bearing brackets bolted to the spine member B, of the base frame work, and affording support for the wire twisting, cutting and effective mechanism.

20 C, is a crank shaft extending through the said bearing brackets B' , B^2 , B^3 , B^4 , and journaled in the aforesaid frontal extensions b^5 , b^6 , of the spine member B, of the frame work, said crank C, being provided at its right hand extremity with a crank 25 handle C' , by means of which the shaft is rotating to effect the twisting of the overlapping ends of the binding wire etc. Rigidly mounted on the crank shaft C, is a driving gear c , positioned in a recess b^x , formed between the opposed sides of the brackets B^2 , B^3 , as shown more particularly 30 in Figs. 4 and 12, of the drawings. Meshing with the driving gear c , which is intermediate in character is the wire twisting gear t , and the lock gear L, both also positioned in the aforesaid recess b^x , within the brackets B^2 , B^3 . The twister gear t , is journaled in and between the brackets B^2 , B^3 , and in the construction and arrangement of 35 parts shown in the drawings its diameter is one half that of the lock gear L, so that it will be rotated twice by the intermediate drive gear c , to every rotation of the lock gear L, thus prescribing the number of convolutions to be effected by the twist. I do 40 not limit myself however in this respect, since it is obvious that by varying the relative diameters of the twister gear t , and the lock gear L, the number of convolutions imparted to the wire w , may be increased or diminished according to requirements.

45 The twister gear t , is formed with the radial slot t' , for the reception of the parallel end strands of the binder wire, the front edges of the brackets B^3 , B^4 , being shaped to afford access to said slot t' , as shown in Fig. 4.

50 Normally the three gears L, c , and t , are held against rotation by a spring bolt s , which engages with a peripheral notch l' , formed for the purpose in the hub l , of the lock gear L, thereby dogging the crank shaft C, through the medium of its intermediate drive gear c , as will be understood by

reference more particularly to Figs. 4 and 13 of the drawings.

55 The lock gear L, is mounted rigidly on a shaft L' , which in turn is supported rotatably in bearings formed for the purpose in the brackets B^2 , B^3 , as shown more particularly in Fig. 13, of the drawings, said shaft L' , extending laterally on either side beyond the brackets B^2 , B^3 , and over the brackets B' , and B^4 , there being held against longitudinal movement by the lock gear L, and its hub l . Rigidly secured to the lock shaft L' , near its outer extremities are thrust cams K, K, against which rest the long arms a , a' , of the rock levers A, A, fulcrumed at a' , a' , in the side walls of the recesses formed 80 for the purpose respectively in the brackets B' , B^4 , (see particularly Fig. 6,) the short eccentric arms a^2 , a^2 , of said rock levers A, A, being in each case in contactual engagement with the head e , of its own spring shear bolt E, said shear bolt E, being slidably mounted in tubular bearings b^7 , bored in the brackets B^2 , B^3 , respectively, and each having a spring e' , interposed between its elongate head e , and the floor of the recess b^x , which spring e' , tends constantly to maintain the engagement of the elongate head e , of the bolt E, with the eccentric end a^2 , of its rock lever A, and also to 85 retract the shear edge e^2 , on the lower extremity of each bolt E, within its tubular bearing b^7 , and out of the adjacent horizontal slot b^8 , formed in each bracket B^2 , B^3 , for the accommodation of the horizontally parallel strands of the binding wire w . The shear ends e^2 , e^2 , of the two bolts E, E, are reversed as related to each other as 90 indicated in Fig. 14, so as to straddle one strand of the binding wire while acting against and severing the other strand thereof, thereby trimming off the superfluous wire at each end of the twist and adjacent to its outer convolutions, as indicated in Fig. 11, it being understood of course that the 95 length of the twist is effective, essentially, to the distance between the two shear bolts E, as indicated in Fig. 8, of the drawings.

100 After the ends of the wire binding loop have been secured together by twisting effected by the rotation of the gear t , they are 105 reversed manually from the gear slot t' , by pushers q^2 , q^2 , mounted slidably in bearings formed for the purpose in the brackets B' , B^4 , as illustrated in Fig. 5 in connection with the bracket B^4 , the parts and structure 110 being duplicated in the bracket B' , and the actuating levers q' , being united at their upper and outer extremities by the cross bar or handle q^2 , so that the twin pushers q , q , are operating simultaneously to effect 115 the ejection of the twisted ends of the binding wire. Retractable springs q^3 , are 120 preferably provided to bear against the 125

lower ends of the actuating levers g' , g' , so that the twin pushers g^2 , g^2 , will return automatically to normal positions when the actuating levers g' , g' , are released.

5 In the use of my improved wire tightening implement the binding wire w , is first passed around the box or package and through the slots b^8 , b^8 , and t' , and then connected with the twin gripping discs G' , $10 G^2$, by means of the radial slots g^8 , g^8 , in the face thereof. The hand lever H , is then reciprocated until the wire is drawn taut around the package. During this tightening operation the crank shaft C , and connection are held locked by the spring bolt s , in engagement with the notch l' , on the hub of the locking gear L . Upon the release of the latter by the withdrawal of said bolt s , the crank shaft C , may be rotated by means 15 of the handle C' , until again locked automatically by the reengagement of the bolt s , (which in the interim rested on the periphery of the hub l), with the notch l' , of the hub l , of said locking gear. During this single rotation of the locking gear L , the twister gear t has been rotated twice (or any other prescribed number of times as hereinbefore explained) the parallel ends of the binding wire thus being twisted securely together. 20

30 The cams K , K , are so timed with relation to the locking gear L , that they act to depress the shear bolts E , E , just prior to the completion of the rotation of said locking gear L , so that the superfluous wire of either 35 extremity of the seal twist is trimmed off automatically beyond the convolutions. After the relocking of the crank shaft C , it connects automatically as above set forth the wire seal of the adjacent portion of the binding wire may be released from the slots 40 manually by a simple expedient of locking the ejector-actuating levers g' , g' , g^2 , after which the implement is ready for further use.

45 My implement is a decided improvement over any other tool of its kind on the market. Heretofore, tools have been put on the market to be used with flat box strapping, which has proven too expensive. Furthermore, with flat box strapping it was necessary to use a certain kind of seal to hold the ends of the strapping together. That system has not proven altogether economical and therefore round wire has been adopted 50 for strapping all kinds of packing cases. With round wire it is not necessary to use any seals, which have a tendency to break off, whereas with round wire the ends of the wire are twisted together, which twist cannot be pulled apart. Round wire therefore, proves more economical. 55

The round wire, when used, is drawn very tightly around the box with the use of a stretching apparatus, until the wire embeds 60 itself into the corners of the box, and then 65

the ends of the said wire are twisted and the protruding ends are cut off. The twist is very strong and of course much stronger than seals. It is very important that the ends of the wire be held securely by the 70 stretching tool, otherwise the wire will give way before the stretching operation takes place. Some tools are so poorly equipped that in order that the wire to be held firm, so that it will not yield when the stretching 75 operation takes place, one end of the wire itself must have a notch or some sort of indentation made in it, to fit in some kind of a groove in the stretching tool and then the end of the wire is pulled until the desired 80 tension is reached. Of course when the wire is required to be thus specially made, the cost of same is necessarily increased over that of plain ordinary wire, which the user can purchase anywhere, without waiting for 85 the manufacturer of the tool to supply him with specially constructed wire. My tool is so manufactured that it will take any kind of wire and I claim therefore, that it is a decided improvement over any other tool of 90 its kind on the market.

In other words my tool is so equipped that an ordinary plain round wire, without any notches or impressions, can be used, this reducing the cost of the wire and it enables 95 the user of such wire to obtain his supplies anywhere, as any steel merchant carries such wire in stock, put up in coils, whereas, if specially manufactured wire must be used, the packer must wait until he could procure 100 his supply and pay a higher price for same, on account of the additional cost of manufacture of the wire. Furthermore the greater tension applied, the firmer the grip on the wire. My tool serves to pull the wire in 105 both directions which saves a great deal of time in applying the necessary tension to the wire. Other tools simply draw the wire from one end; in my tool, as the wheels turn, the wire is held more securely, thereby enabling the operator to apply a very strong 110 tension on the wire.

A distinctive feature is that the holding wheels travel in either direction, thus causing the tension to be performed much more 115 quickly than if the wire were pulled only from one direction. I claim, therefore, this to be a decided improvement over any other tool on the market.

What I claim as my invention and desire 120 to secure by Letters Patent, is:—

1. In a device for securing wire binders of the character designated, the combination of twin clutch discs, means for rotating said clutch discs simultaneously in opposite directions, means for twisting the superposed strands of wire held therebetween, a locking means, and means operating in conjunction with said locking means for severing the superfluous wire from the twisted portions 125 130 135

thereof, substantially in the manner and for the purpose set forth.

2. In a device for securing wire binders of the character designated, the combination of twin clutch discs, means for rotating said clutch discs simultaneously in opposite directions, means for twisting the superposed strands of wire held therebetween, means for automatically limiting the twists convolutions imparted to the superposed portions of the wire, a locking means, and means operating in conjunction with said locking means for severing the superfluous wire from the twisted portions thereof, substantially in the manner and for the purpose set forth.

3. In a device for securing wire binders of the character designated, the combination of twin clutch discs, means for rotating said clutch discs simultaneously in opposite directions, means for twisting the superposed strands of wire held therebetween, a locking means, means operating in conjunction with said locking means for automatically limiting the twists convolutions imparted to the superposed portions of the wire, and means for severing the superfluous wire from the twisted portions thereof, together with means for ejecting the convoluted ends of the wire strands from the twisting mechanism, substantially in the manner and for the purpose set forth.

4. In a device for securing wire binders of the character designated, comprising a hand power shaft, a lever and ratchet mechanism for actuating the same intermittently, countershafts, and gears drive pinions on said power shaft opposed in position as related to each other and meshing with said gears or countershafts, and twin wire gripping discs, one mounted on each of said countershafts, locking means and wire severing means timed with relation to the locking means to sever the wire just prior to the complete rotation of the locking means for the purpose and substantially in the manner set forth.

5. In a device for securing wire binders of the character designated, comprising twin wire tightening discs and means for rotating same in opposite directions, a crank shaft and drive gear, and a wire twisting gear meshing with said drive gear, a locking gear cooperable with the twister gear, a shear bolt timed relative to the locking gear to sever the superfluous wire after being twisted substantially in the manner and for the purpose set forth.

6. In a device for securing wire binders of the character designated, comprising twin wire tightening discs and means for rotating same in opposite directions, a crank shaft and drive gear, wire twisting gear meshing with said drive gear, and a lock gear meshing with said drive gear, wire severing means timed with relation to the

locking means to sever the wire just prior to the completion of rotation of the locking means and releasable means for automatically limiting the rotation of said lock gear, substantially in the manner and for the purpose set forth. 70

7. In a device for securing wire binders of the character designated, comprising twin wire tightening discs and means for rotating same in opposite directions, a crank shaft and drive gear, wire twisting gear meshing with said drive gear, and a lock gear meshing with said drive gear, and releasable means for automatically limiting the rotation of said lock gear, together with means co-operable with the lock gear for automatically trimming the wire twist, substantially in the manner and for the purpose set forth. 80

8. In a device for securing wire binders of the character designated, comprising twin wire tightening discs and means for rotating same in opposite directions, a crank shaft and drive gear, wire twisting gear meshing with said drive gear, and a lock gear meshing with said drive gear, a shear bolt cooperably timed relative to the locking means to sever the superfluous wire after being twisted and releasable means for automatically limiting the rotation of said lock gear, together with means for manually ejecting the twisted ends of the wire binder, substantially in the manner and for the purpose set forth. 90

9. In a device for securing wire binders of the character designated, comprising twin wire tightening discs and means for rotating same in opposite directions, a crank shaft and drive gear, a wire twisting gear meshing with said drive gear, and a lock gear meshing with said drive gear, and releasable means for automatically limiting the rotation of said lock gear, together with means co-operable with the lock gear for automatically trimming the wire twist, substantially in the manner and for the purpose set forth. 100

10. In a device for securing wire binders of the character designated, comprising twin wire tightening discs and means for rotating same in opposite directions, a crank shaft and drive gear, a wire twisting gear meshing with said drive gear, a lock gear meshing with said drive gear, a shear bolt timed relative to the locking gear to sever the superfluous wire after being twisted and releasable means for automatically limiting the rotation of said locking gear, cams mounted on the shaft of said locking gear, rock levers actuated by said rock levers, substantially in the manner and for the purpose set forth. 110 115

11. In a device for securing wire binders of the character designated, comprising twin wire tightening discs and means for

rotating same in opposite directions, a crank shaft and drive gear, a wire twisting gear meshing with said drive gear, a lock gear meshing with said drive gear, a shear bolt mounted on the shaft of said locking gear, rock levers actuated by said rock levers, together with means for manually ejecting the twisted ends of the wire binder.

timed relative to the locking gear to sever the superfluous wire after being twisted and releasable means for automatically limiting the rotation of said locking gear, cams
